UNITED STATES PATENT OFFICE.

EDWARD H. LEVEAUX, OF THE CHASE, CLAPHAM COMMON, COUNTY OF SURREY, ENGLAND.

APPARATUS FOR STORING AND TRANSMITTING MOTIVE POWER, &c.

SPECIFICATION forming part of Letters Patent No. 247,993, dated October 4, 1881.

Application filed August 29, 1881. (No model.) Patented in England February 27, 1879, in France August 27, 1879, in Germany September 30, 1879, and in British India February 26, 1880.

To all whom it may concern:

Be it known that I, EDWARD HENRY LEVEAUX, of The Chase, Clapham Common, in the county of Surrey, England, have invented certain Improvements in Apparatus for Storing and Transmitting Motive Power and for Indicating the Supply and Expenditure of the Same, 5 of which the following is a specification.

This invention relates to an improved arrangement of spring mechanism for driving machines or carriages; also to the means for indicating the amount of motive force supplied to or contained at any given moment in such spring mechanism.

15 The apparatus consists of a series of coiled springs fitted to containing-barrels, the number of such springs and barrels being determined by the amount of motive force required to be stored.

20 In apparatus of this class as heretofore constructed the barrels of the whole series were so connected together that all the coiled springs, when the apparatus was started, would come into action simultaneously. Thus the motive force of the last spring of the series would be delivered to the driving-shaft through all the springs of the series, and thereby an undue amount of friction was created. I now propose not only to obviate this inconvenience, but also 25 to provide means for indicating the amount of motive force supplied to or contained at any given moment in each set of the spring-barrels.

The apparatus may contain one, two, or more sets of these spring-barrels, and the sets 30 will each be wound up by direct connection with the shaft, which is the source of power.

In Sheets I and II of the accompanying drawings I have shown an arrangement of motive-power apparatus suitable for driving fixed 35 or stationary machines—such, for example, as sewing-machines—Figure 1 being a plan view of the apparatus; Fig. 2, a partial sectional elevation taken in the line 1 2 of Fig. 1, and Fig. 3 a partial sectional elevation taken at 40 right angles to Fig. 2 and in the line 3 4 of Fig. 1.

In this arrangement of apparatus two sets of barrels only are shown; but it will be pres-

ently manifest that any desired number of sets may be combined to make the motive force of 50 the apparatus equal to working a driving-shaft for any desired number of hours. These sets are composed each of three barrels, A, which barrels each contain two coiled springs, B B', the spring B coiling, say, to the right and the 55 spring B' to the left, and so on throughout the series. The sets of barrels A are mounted loosely on dead-axes C, fixed to the frame D of the apparatus. Strung upon these dead-axes C are short sleeve-arbors E E' E'', and it 60 is upon these that the barrels are respectively loosely mounted. The sleeve E of each set of barrels enters its barrel and extends to about the middle of the barrel's length, in order that a coiled spring, B, may be attached thereto, 65 the other end of which spring is attached to the barrel. In like manner the spring B' in the same barrel is connected at one end to the barrel and at its other end to a second sleeve, 70 E', which sleeve extends into the next adjacent barrel, to connect with the spring B of that barrel, and thus in like manner all the springs in the set are connected with their respective barrels and sleeves. The sleeve E'', which is the last of the series of sleeves, carries external of its barrel a chain-wheel, for giving off 75 the power of the set of spring-barrels, as will be hereinafter explained. This chain-wheel is fitted with a friction - surface for receiving a 80 brake-strap, which serves to hold the end sleeve-arbor stationary while the winding up of the apparatus takes place.

For winding up the barrels of the several sets simultaneously the following contrivance is employed: Keyed upon each sleeve-arbor E 85 is a worm-wheel, F, into which gears a worm, G, mounted loosely on a winding-shaft, H, and made fast thereto by a sliding clutch, which is held in the locking position by the pressure of a coiled spring, and is capable of being disengaged from the worm, as will be presently explained. When rotary motion is imparted to the shaft H by a winch-handle or equivalent means the barrels and sleeves will be caused to wind up their coiled springs, and thus a 90 store of motive force will be obtained. For

giving out this force to a driving-shaft, I, the chain-wheels K K are employed.

Mounted loosely on the shaft I are chain-wheels L L, which receive motion from the wheels K by the chains L. By the side of these wheels L are ratchet-wheels M, which are keyed to the shaft I, and by means of pawls carried by the bosses of the chain-wheels a connection will be established between them 10 and the ratchet-wheels M; or the chain-wheels L may be formed with a ring of ratchet-teeth to receive pawls carried by a disk, as at M, keyed to the driving-shaft I.

For driving the shaft I, which is to give off 15 its power to the machinery required to be actuated, it is only necessary, when the barrels are wound up, to release one or more of the retaining-brakes, and the chain-wheels K (one or more) will be set in action and caused to 20 impart a rotary motion to the shaft I.

In order that the amount of power expended may be determined at a glance, the apparatus is provided with an indicator, the nature of which I will now explain.

25 Adjacent to each main wheel F, and on the same arbor, is a spur-wheel, N, for transmitting rotary motion through a spur-wheel, O, to a screw-shaft, P, lying parallel with the barrels. This wheel O has its bearings in the framing, 30 and through it one end of the shaft P passes, it being connected thereto by a feather. To the screwed end of this shaft is fitted loosely a spur-wheel, Q, with a threaded boss, such wheel being mounted in the framing, so that 35 it may act as a stationary nut. This wheel is driven from a spur-wheel, R, keyed to the sleeve-arbor E² of the last spring of the set.

On the screw-shaft is mounted loosely between fixed collars a block, S, which carries 40 a pointer. This pointer S, as the shaft is moved endwise by reason of the rotation of the spur-wheel Q, travels over a graduated scale fixed to a table carried by the framing D and slotted to allow of the pointer reaching to the 45 scale. This slot (shown at T) also forms a guide for the traversing block S. The pointer will thus indicate, according to the direction of its movement, either the progress of the winding up of the barrels or the unwinding of 50 the coiled springs and the expenditure of the stored power. The endwise traverse of the screw-shaft I use to throw the clutch before mentioned out of gear when the barrels are wound up, and thereby to stop the further action 55 of the driving-shaft. To this end the space corresponding with the traverse motion of the pointer is embraced by a sliding piece, U, fitted in the slot T of the table. This sliding piece carries an incline at one end, against 60 which incline lies a bowl carried by one end of a rock-lever, V, the other end of which terminates in a fork that embraces the sliding clutch. As the set of barrels is wound up the 65 pointer advances, and, pressing against the slide, causes its incline to tip the rock-lever, and thereby throw the clutch out of action.

As, however, the force of the springs is being given off the pointer will travel back, and, striking the slide U as the power becomes expended, it will release the rock-lever and allow 70 the spring-clutch to lock the worm G to its shaft.

As each set of spring-barrels is similarly provided with the above-described indicator, and each has also its brake-wheel and chain wheel, 75 it will be obvious that the motion of each set will be independently transmitted to the receiving or transmitting shaft I, and in succession or simultaneously, as thought desirable.

In Sheets III and IV of the drawings I have 80 shown my above-described apparatus as arranged for use in a tram-carriage, Fig. 4 being a partial plan view of the apparatus, and Figs. 5, 6, and 7 sectional elevations taken respectively in the lines 5, 6, 7, 8, 9, and 10 of Fig. 4. 85

As the same letters of reference are used in Sheets I and II for the like parts, a repetition of the preceding description will be unnecessary. It will only, therefore, be requisite to explain the means adopted for bringing the indicating apparatus within view to suit the special requirements of the case.

The block S, instead of carrying the pointer, is now provided with a pin, which takes into 95 the arm S' of a rock-shaft, S², having its bearings in the framing of the carriage. An arm, S³, at the forward end of this shaft, and set at right angles to the arm S', is connected to a vertical sliding bar, S⁴, to which the pointer S⁵ is attached. Adjacent to this pointer is a graduated scale, S⁶, upon which is indicated, by means of the rise and fall of the pointer, the traverse of the block S, and consequently the state of the winding-up apparatus, both as respects the amount of winding up effected and the amount 105 of power given off by the coiled springs.

Having now set forth the nature of my invention of improvements in apparatus for storing and transmitting motive power and for indicating the supply and expenditure of the 110 same, I wish it to be understood that I claim—

1. The arrangement of apparatus above described, consisting of a set or sets of spring-barrels, A, and sleeve-arbors E E' E², strung loosely upon a dead axle or axles, C, the barrels and sleeve-arbors of each set being connected together by coiled springs B B', such springs being wound up by worms and worm-wheels and prevented from uncoiling by friction-brakes or their equivalent, the end sleeve-arbors carrying chain-wheels K, for transmitting 115 through endless chains motion directly to a common shaft, whereby motive power may be stored in independent sets of barrels, and may be given off from one set at a time or from 120 all the sets simultaneously, as desired.

2. In combination with a set or sets of spring-barrels, arranged as described, the traveling indicator S, mounted on a screwed shaft, P, which receives rotary motion from the first 125 sleeve-arbor, E, and an endwise motion from the threaded hub of the wheel Q, which is driven

from the last sleeve-arbor, E², such traveling indicator serving to show at all times the extent to which the springs have been wound up or unwound.

5. 3. In combination with the screwed indicator-shaft P, the sliding piece U, for throwing out of action through a rock-lever, V, or its equivalent, the clutch which connects the worm G with its driving-shaft, and thereby prevents

the possibility of overwinding the coiled springs.
